UNITED STATES PATENT OFFICE.

JULIUS HERBST, OF MILWAUKEE, WISCONSIN.

EXPANSIBLE COVER FOR SHOE-STRETCHERS.

SPECIFICATION forming part of Letters Patent No. 587,965, dated August 10, 1897.

Application filed March 17, 1897. Serial No. 628,051. (No model.)

To all whom it may concern:

Be it known that I, JULIUS HERBST, of Milwaukee, in the county of Milwaukee and State of Wisconsin, have invented a new and 5 useful Improvement in Expansible Covers for Shoe-Stretchers, of which the following is a description, reference being had to the accompanying drawings, which are a part of this specification.

10 My invention has relation to improvements in expansible covers for shoe-stretchers.

The use of shoe-stretchers is open to more or less objection owing to the fact that said stretchers are constructed of parts which are 15 adapted to be separated in order to effect the stretching of the shoe. When the adjusting mechanism of the stretcher is operated so as to separate the sections, openings are formed which leave parts of the shoe unsupported.

20 The object of my invention is to provide an expansible cover to bridge over these openings and to thereby support the shoe at all points and fill out the places which are left unsupported by the stretcher.

25 With the above primary object in view the invention consists of the devices and parts or their equivalents, as hereinafter more fully set forth.

In the accompanying drawings, Figure 1 30 is a side elevation of my improved expansible covering applied to an ordinary shoe-stretcher. Fig. 2 is a plan view of Fig. 1. Fig. 3 is a bottom view of the covering removed from the stretcher, and Fig. 4 is a 35 bottom view of a modified form of covering.

Referring to the drawings, the numeral 5 indicates a shoe-stretcher which, being of ordinary construction and forming no part of my invention, excepting so far as it combines 40 and operates in connection therewith, requires no specific description.

The covering is preferably made of leather or similar material and consists of the main portion 6, which is so shaped as to conform 45 to the shape of the stretcher over which it is adapted to be placed. The free edges of the covering are arranged on the underside thereof and these edges are adapted to overlap freely, so as to permit the giving or expand- 50 ing of the covering at the bottom thereof with the different adjustments of the stretcher. In the form illustrated in Figs. 1, 2, and 3 these

overlapping edges are formed with V-shaped registering slits 7 7, which together form a diamond-shaped opening. The edge 8, which 55 extends rearwardly in one direction from this opening, overlaps the corresponding edge 8' of the other side, and the edge 9 of this latter side, which extends from the diamond-shaped opening to the front of the covering, overlaps 60 the corresponding edge 9' of the other side. This particular manner of overlapping is not absolutely necessary, as the edges on one side could both overlap the edges of the opposite side. 65

The top of the covering is slitted longitudinally for a considerable distance, as indicated at 10, and this slit provides for a requisite give or expansion of the upper portion of the covering with the different adjustments 70 of the stretcher. In order to bridge over the opening formed by this slit, (which opening of course enlarges considerably as the stretcher is adjusted,) and to thereby support the shoe at this point, I provide the lip or 75 tongue 11, which is stitched at 12 to the covering and is free for the remaining portion of its length. This lip or tongue is of considerable width, especially at or near its center, and is preferably composed of stiff leather. 80

As is well known, the usual form of shoe-stretcher consists of two longitudinal sections hinged at their rear. The edges of these sections are adapted to be adjusted closer together or farther apart by means of an adjusting-screw provided with a suitable wedge which acts against the opposed edges of the stretcher. The stretcher 5 (shown in the accompanying drawings) is of this form, and it is obvious that when the stretcher is inserted 90 into a shoe and the sections of the stretcher separated by means of the screw spaces are left between the separated edges because of the hinged and varying angular or oblique positions of parts, especially below the instep 95 and just at the rear of the ball of the foot. By providing my improved covering, however, which is adapted to be inserted over the stretcher before the latter is placed within a shoe, these objections are successfully overcome, as the expansible cover bridges over the openings and supports the shoe at all points and fills out places not supported by the stretcher. 100

The form of stretcher illustrated in Fig. 4 and designated by the numeral 6' is similar to the form shown in Figs. 1, 2, and 3, except instead of providing the registering V-shaped 5 slits in the edges of the covering at the under side thereof one edge simply overlaps the other for a considerable distance, as clearly shown.

The form illustrated in Fig. 3, wherein a 10 slit is provided medially on the under side, (which slit need not necessarily be of the peculiar shape shown,) may be advantageously used, inasmuch as said slit provides for the covering better adapting itself to the shape of 15 the shoe—that is to say, if the toe of the shoe is smaller than the covering then said covering can expand at the heel and consequently contract at the toe portion, or if the toe of the shoe is larger than the toe of the covering 20 then the heel portion of the covering can contract and the toe portion expand. The same is true in regard to the heel portion of the covering, which is also susceptible of readily adapting itself to a shoe having a heel portion 25 larger or smaller.

It will be obvious that my invention can be most advantageously used by repairers when putting patches on shoes or adjusting toe-tips to shoes or for the purpose of merely stretching a shoe, filling the shoe out perfectly, and thus enabling the above to be accomplished 30 much more efficiently than it is now possible to do.

What I claim as my invention is—

35 1. As an improved article of manufacture, an expandible covering for shoe-stretchers.
2. The combination with a shoe-stretcher consisting of separable or adjustable sections, of an expandible covering for the stretcher,

adapted to bridge over the openings formed 40 by the stretcher, when the parts thereof are separated.

3. As an improved article of manufacture, a covering for a shoe-stretcher, composed of suitable material and shaped to fit the 45 stretcher, and having its edges free and overlapping.

4. As an improved article of manufacture, a covering for a shoe-stretcher, composed of suitable material, and shaped to fit the 50 stretcher, and having its free edges formed with registering slits to provide an opening.

5. As an improved article of manufacture, a covering for a shoe-stretcher composed of suitable material, and shaped to fit the 55 stretcher, and provided with a longitudinal slit.

6. As an improved article of manufacture, a covering for a shoe-stretcher composed of suitable material, and shaped to fit the 60 stretcher, and provided with a longitudinal slit, and a lip or tongue secured to the covering and bridging over the longitudinal slit.

7. As an improved article of manufacture, a covering for a shoe-stretcher composed 65 of suitable material, and shaped to fit the stretcher, and having its free edges on its under side overlapping; and provided with a longitudinal opening in its top, and a tongue or lip secured to the covering and bridging over 70 the longitudinal opening in the top.

In testimony whereof I affix my signature in presence of two witnesses.

JULIUS HERBST.
